ELECTRIC SIGNALING SYSTEM

Robert W. Richardson, Cleveland, Ohio

Application April 2, 1929, Serial No. 351,993

2 Claims. (Cl. 177—311)

This invention as indicated relates to an electric signaling system. More particularly it comprises a readily variable device suitable for indicating the number of units or articles available or to be supplied and for stepping up or down the visual indication from any one of a plurality of stations. The device may be used in a restaurant to indicate the number of orders awaiting delivery, from the kitchen, of each special item on the menu which requires the attention of the cook, or may be used to indicate the number of units on the branch assembly lines of a manufacturing establishment, such as an automobile assembly line, or may be used to show the number of cabs at various cab stations. The instances mentioned are merely illustrative and by no means exhaustive inasmuch as the device is applicable to quite varied uses and certain parts of the apparatus may be found of advantage in connection with advertising signs or for purposes of various kinds wherein selective operation of one or more of a plurality of electrical circuits is desirable with controls operable from any one of a number of different stations. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

35 In said annexed drawings:—

Fig. 1 is a perspective view showing in outline, the kitchen and service counter of a restaurant equipped with the signaling system embodying the principles of my invention; Fig. 2 is a wiring diagram showing three banks of indicator lamps and three control switches therefor; Fig. 3 is a central vertical sectional view, one of the selective drum switches used in my signaling system; and Figs. 4 and 5 are enlarged diagrammatic views of the terminal-carrying discs of the switch illustrated in Fig. 3.

As will appear from Fig. 1 of the drawings, the apparatus illustrated is a three-unit system, and comprises an indicator device 1 adapted to be mounted on the wall of the kitchen of a restaurant, a control unit or bank of switches 2 mounted on the service table 3 of the kitchen adjacent the delivery window shelf 4 which extends into the dining room portion of the restaurant adjacent the service counter 5 upon which

two cabinets 6 are mounted. Each cabinet 6 is provided with a control unit or bank of switches 7 adjacent its lower edge but obviously the position of the control units and indicator cabinets may be varied to suit the convenience of the operators. Thus the dining room indicators may also be mounted on the wall as in the kitchen installation illustrated, and the respective switch banks may be disposed at any convenient positions in the dining room. Also one indicator may serve a number of control units, or for some special uses of the device, the number of indicator panels or cabinets may exceed the number of control units. 5

Various types of indicators may be employed, 15 that illustrated comprising a cabinet provided with a series of successively numbered rows of windows behind which are disposed electric lamps. The indication may be given by placing a selected lamp in any row in circuit or by having one 20 lamp in any row show brighter than the other lamps in said row. Drop panels or any other indicating devices may be used instead of lamps if desired. 15

In the wiring diagram shown in Fig. 2, the electrical connections suitable for operating from three control units, one lamp in a twelve lamp row in three separate panels or cabinets is illustrated. It is to be understood that each of the remaining three switches shown in each control 30 unit in Fig. 1 will have a similar set of wiring connections to its corresponding rows of lamps in the indicator panels. Obviously the number of switches in each control unit and the number of rows of lamps in each panel may be any number 35 required for a particular use. Any suitable source 40 of electrical current may be employed, one line 12 in the apparatus shown in Fig. 2 being connected to the shaft of the dial switch 13 which is provided with a number of contact studs 14 corresponding to the number of lamps in each row of the indicator, and one extra line to provide for a non-indicating position, as will presently be explained. The shaft is provided with a control knob 15 and a contact arm 16, whereby contact 45 may be made by said arm with any one of the studs carried by the switch. The studs are mounted in an insulating disc 17 and a suitable casing for the series of switches may be provided as is shown in Fig. 1. Individual wires 18, 18a, 50 18b, etc., from each of the studs are carried to corresponding contact studs 21 in an insulating disc 22 carried in slip ring or drum type switch 23 forming one of the banks of switches 7 shown in Fig. 1. Said switch 23 is provided with a suit- 55

- able frame or casing 24 to the bottom of which the disc 22 is rigidly secured. Within the casing a shaft 25 of insulating material is mounted, said shaft being adapted to be turned by the knob 26.
- 5 As will more clearly appear from Fig. 3 of the drawings, the shaft is a tubular fiber member held in a socket 27 at the lower side of the casing by a spring 28, and carries a number of copper slip rings 28a, 28b, etc., suitably insulated from each other by means of insulating discs 29. Each slip ring is connected by a wire 30 with its individual terminal 31 carried on a disc 32 mounted adjacent the lower end of the shaft. Each terminal comprises a binding screw against which a spring 33 engages and below which spring a brush 34, of suitable conducting material, is seated. The ends of the brushes are adapted to make contact with the studs 21 forming the terminals of the wires from the switch 13.
- 20 A block of insulating material held at the side of the casing forms a brush holder 35 for the individual contacts for the respective slip rings. Each of these contacts comprises a brush 36, 36a, 36b, etc., pressed outwardly by a spring 37 and having a terminal member 38 formed with a brass binding screw beneath which individual wires leading to a similar switch 40 may be engaged. The switch 40 is of substantially identical construction with that of the switch 23 and the wires 39, 39a, 39b, etc., leading from the switch 23, connecting with contact studs 41, 41a, 41b, etc., on a disk 42. The rotating contact member is identical with that shown in Fig. 3. Wires 44, 44a, 44b, etc., are connected to brushes 45, 45a, 45b, etc., and are each in circuit with a lamp 51 in one row of the indicator 1 and a lamp 52 in one row of one of the indicators 7 and a lamp 53 in one row of the other indicator 7, in series with each other. The circuit is completed by means of the wires 44, 44a, 44b, etc., connecting to the other terminal of the current source 11, through a trunk line 46 and connection 47.
- 45 With the mechanism just described, the circuit may be closed through any of the series of lamps illustrated in Fig. 2. Thus with the contact arm 16 making contact with the wire 18b which terminates in the stud 14 on the disc 17, the current will flow through the brush 36 and the connecting wire 39 to the slip ring 28; thence it will flow through the brush 36 and its associated wire 39 to the stud 41 of the switch 40 and through its connections to the brush 45 and the conductor 44 to the lamps 51, 52, 53, and thence through the trunk line 46, and connection 47 to the current source 55.
- 50 It will be obvious that if the arm 16 of the switch 13 is turned to contact with another stud such as the stud 14a, current will then flow through the line 18a, brush 34a, slip ring 28a, brush 36a, conductor 39a, contact 41a, on the switch 40, and through its connections to the brush 45a and conductor 44a which is in circuit with the lamps 51a, 52a, 53a, instead of the lamps 51, 52, 53. If the arm 16 should be turned in the other direction to contact with the stud 14b, 51b, 52b, and 53b, would be connected in circuit instead of those originally mentioned.
- 55 If, instead of turning the arm 16 of the switch 2, the disc 31 of the switch 23 was turned in a like direction one contact point, a like result would take place. The same action would also take place if the switch 40 was turned in like manner. If all three switches were turned in the same direction the indicator lamps would be

stepped up or down, depending upon the direction of movement of the switches, three points.

It will thus be seen that there is but one circuit established at one time through the apparatus, but that the circuit path may be varied by any one 5 of the switches at any time and that the movement of one of the switches is entirely independent of the movement of the others but that the indicator will respond to the total relative displacement of all of the switches from the position 10 originally occupied.

It will appear from Fig. 2 that there is one more set of circuit connections through the switches 13, 23, and 40, than there are lamps in each row. Thus there are twelve lamps in each row and 15 thirteen circuit connections. It will be noted that the last of the three switches, the switch 40, has no connection for the topmost slip ring 60. This permits a non-indicating position to be set by turning any switch or combination of switches to 20 connect said slip ring 60 with the current source.

Where the device is to be used in a restaurant, a convenient manner of handling orders would be to label one row of lamps for an order such as roast beef and other rows of lamps for orders re- 25 spectively of roast veal, roast pork, ham and eggs, and the like. Each row of lamps under each of these designations would be serially numbered from 1 to the total number of lamps installed in the row. Like indicators would be available in 30 the kitchen and dining room, and, if desired, an indicator could accompany each switch. When an order for roast beef was received by a waiter in the dining room, this order would be transmitted to the kitchen by turning the switch 35 knob in the roast beef column in a direction to add a higher number to that showing in the roast beef column. When an order of roast beef is delivered from the kitchen to the dining room, the switch in the kitchen would be turned in a direction 40 to show a lower numbered indication in the roast beef column. Suitable ratchet mechanism 61, 62, 63 might be employed on the respective switches to permit only clockwise movement of the switches 23, and 40, and counter clockwise 45 movement of the switch 13. While a ratchet mechanism for movement in one direction has been shown in the drawings, it is to be understood that the apparatus will operate without a ratchet mechanism and that for purposes of cor- 50 recting errors such ratchet mechanism may be omitted or made readily releasable, as otherwise errors would have to be corrected by moving the indicator through substantially the entire swing of the dial in place of moving it back one step for 55 an error of one number.

The same system of operation would be readily applicable to the assembly line of a manufacturing plant, such as an automobile assembly line wherein a number of small parts were in use and 60 the quantity remaining available would be readily apparent from an inspection of the indicator. Likewise the device as applied to cab stands in various parts of the city would show at all times the number of cabs at a particular station and 65 permit a distribution of the available vehicles to the best advantage.

As has been indicated, the system of control may be applied to many other mechanisms other than those referred to and the individual parts of 70 the apparatus may likewise be used for very specific services other than those herein described.

Other modes of applying the principle of my invention may be employed instead of the one explained, change being made as regards the 75

mechanism herein disclosed, provided the means stated by any of the following claims or the equivalent of such stated means be employed.

I therefore particularly point out and distinctly claim as my invention:—

- 5 1. In an electrical signaling system, a plurality of indicator units, a plurality of rows of signaling elements in each indicator unit, an electric circuit connected with a source of power by two single conducting elements, one of said elements connected with a single contact member movable relatively to a series of opposite contact members each connected with separate parallel circuits each having in series corresponding signaling elements of corresponding rows in each indicator, a plurality of selective switches carrying contacts in said parallel circuits, each of said switches having a series of fixed contacts equal to the total number of signaling elements in a row, and each switch having a movable member having individual contact members equal to the number of fixed contacts and movable thereover in circuit changing relation, said movable member carrying collector rings equal in number to the number of individual contact members and individually connected therewith respectively, and individual brushes equal in number to the number of collector rings and connected in separate parallel circuits with said respective signaling elements, and the other single conducting element connected with the source of power having common connection with all of said parallel circuits through said signaling elements and switches.
- 10 2. An apparatus of the character described

having in combination a source of electric current, a plurality of indicator elements connected with one terminal of said source of current, a plurality of conductor elements connected individually with said indicator elements respectively at one end and having a fixed terminal member at the opposite end forming part of a series of terminal elements, a movable contact member connected with the opposite terminal of said source of current, a plurality of parallel conductor elements having a terminal at each end and adapted to be selectively placed in circuit with said source of current by said movable contact member engaging one set of such terminals, a rotatable member interposed between the other set of terminal members of said parallel conductor elements and the series of terminal elements of the set of conductors extending to said signaling elements, said rotatable member having a plurality of parallel conductor elements terminating at one end in collector rings adapted to contact the respective members of the series of terminal elements on the group of conductors connected with said signaling elements and having a plurality of movable contact members adapted to contact the terminal elements on said parallel conductor elements connected with said movable contact member, whereby any signaling element may be selectively energized through movement of said movable contact member or through movement of said rotatable member, each independently of the other.

ROBERT W. RICHARDSON.
